FIG. 2.

FIG. 3.

Inventor
A. F. DUNSMORE
By Johnston & Son Atty.

UNITED STATES PATENT OFFICE.

ALEXANDER FRASER DUNSMORE, OF GLASGOW, SCOTLAND.

HYDRO-EXTRACTOR OR CENTRIFUGAL MACHINE.

Application filed February 16, 1927, Serial No. 168,760, and in Great Britain December 30, 1926.

This invention relates to improvements in hydro-extractors or centrifugal machines particularly such as are used for removal of water from clothes and the like.

- 5   The invention has for its object to provide in such a machine improved means for preventing access of fog, soot, etc., to the interior of the machine basket and thus soiling the contents of the basket.
- 10   According to the invention there is provided for removable attachment to the machine spindle, so as when in position to form a cover for the basket, a preferably sectional skeleton or apertured frame having
- 15   panels formed as filters, e. g., of triple filter fabric, so contrived that the filter fabric is not subject to undue tearing stresses in the operation of the machine and that the panels may be individually removed and ex-
- 20   changed if and when required.

The panelled frame may be automatically locked to the rim of the basket while the machine is in operation.

For attachment of the frame to the spindle it is preferred to fit to the spindle a socketed collar pinched to the spindle by a set pin or the like and the frame is formed with a bush adapted to fit the socket in the collar. As is understood, if the frame is 30 sectional, the bush is split. For example, the frame proper may comprise two complementary semi-circular elements having radial spokes with panels filling the gaps between the spokes and clamped to the spokes by straps secured by screws or the like, or the frame may be formed with apertures of any desired form and number and closed by filter panels.

There may be pivoted to the periphery of 40 the frame on the under side swing bolts, which, when the machine is stationary, hang clear of the basket rim but which in the operation of the machine fly out under the action of centrifugal force and engage beneath the rim.

The invention is equally applicable to top-driven and under-driven machines, it being understood that when the machine is top-driven the frame requires to be sectional, the 50 sections being dropped into position so that the split bush fills the socket in the collar. Alternatively, the collar may be formed with a socket on the under side and be

mounted above instead of below the frame for sliding movement on the spindle. 55

In the accompanying drawings Fig. 1 is a fragmentary vertical section of a hydro-extractor with attachment according to the invention; Fig. 2 is a plan view of the attachment; Fig. 3 is a fragmentary section to an enlarged scale of the rim of the attachment frame.

Referring to the drawings, 1 denotes the spindle of a hydro-extractor on which is pinched by means of a set pin 2 a socketed 65 collar 3. Engageable with the socket in the collar 3 are the sections of a split bush 4 unitary with the sections of a skeleton circular frame having spokes 5 connecting the bush with the annular rim 6, the gaps between the spokes being filled with panels 7 of filter fabric nipped between the frame and straps 8 removably secured to the frame by screws 9.

The panelled frame when in position 75 forms a cover for the basket 10.

Pivoted to the annular rim 6 of the frame on the under side are weights 11 which when the machine is stationary hang clear of the basket rim 12 but which in the operation of 80 the machine fly out under the action of centrifugal force and function as swing bolts engageable with the under side of the basket rim.

What I claim is:—

1. In a hydro-extractor, in combination with a rotary spindle, a basket rotatable with said spindle, a socket held to said spindle, and a panelled frame to form a cover for said basket, said frame having a bush 90 engageable with the socket, the panels of said frame being removable and composed of filtering medium.

2. In a hydro-extractor, in combination with a rotary spindle, a basket rotatable 95 with said spindle, a socket held to said spindle, and a sectional panelled frame to form a cover for said basket, said frame having a bush engageable with said socket, said bush comprising sections each unitary with 100 a sector of said frame.

3. In a hydro-extractor, in combination, a rotary spindle, a basket rotatable with said spindle, and having an inturned rim presenting a central aperture, a socket held to 105 said spindle a panelled frame removably at-

tached to said spindle to close said aperture, said frame having a bush engageable with said socket the panels of said frame being removable and composed of filtering medium, and means for locking said frame to said rim automatically in the rotation of said basket.

4. In a hydro-extractor, in combination, a rotary spindle, a basket rotatable with said

spindle, a skeleton frame, panels of filtering medium fitted to said frame, straps between which and said frame said panels are nipped, and means for removably attaching said frame to said spindle to form a cover for said basket.

In testimony whereof I have signed my name to this specification.

ALEXANDER FRASER DUNSMORE.
